RAILROAD SPIKE.

Application filed May 2, 1925. Serial No. 27,370.

This invention relates to improvements in railroad spikes for fastening track rails and rail plates, either or both, to wood crossties. Its object is to produce such a spike in a form which when driven into wood can neither turn axially nor back out and which when driven will then so tightly plug the upper end portion of the hole formed in the wood by the driven spike that water will be excluded from the joint thereby formed, and rotting of the wall of the hole and loosening of the spike in consequence of rotting, prevented. The strikingly novel feature of our new spike lies in the hereinafter described variant diameters of its shank between the spike neck and the under wood cutting and penetrating end of the spike.

In the accompanying drawings forming a part hereof and illustrating our invention, Fig. 1 is a vertical, side elevation of our new spike in rail clamping position, the spike shank extending through a hole in a rail plate and downwardly into a wood cross-tie both indicated in vertical section.

Fig. 2 is an elevation of the spike, looking at its inward or rail facing side removed.

Figs. 3, 4 and 5 are, respectively, cross-sectional views of the cross-sectionally round spike shank at lines 3-3; 4-4; and 5-5 of Fig. 2, and indicate the variant diameters of the spike shank.

In the drawings, our new railroad spike comprises a head 1 having a track rail base flange clamping extension 2 and side flanges 3 for engagement by a spike pulling implement when the spike is to be pulled. Immediately under the clamping extension 2, the spike neck which is preferably quadrangular in cross-section, has an inwardly facing, rail flange edge bearing wall 4. At its under end, the spike neck merges into the upper end of the relatively elongated straight shank which is cross-sectionally round throughout its length down to its cross-sectionally polygonal, downwardly tapered, wood penetrating end, which is preferably made quadrangular in cross-section with two opposed, downwardly convergent, elongated flat walls 5 each angularly intersecting with each of two other opposed walls 6. These opposed angularly intersecting walls serve to prevent the driven spike from turning axially in its hole and

they also form, adjacent and extending slightly above the under wedge shape driving down 7, wood cutting corners 8. From above the upper ends of the flat walls 5 and 6 to the under end of the spike neck, the shank is continuously round in cross-section, except for a lengthwise extending rib projecting radially from its reversed intermediate section.

In accordance with this invention, the cross-section or upper shank portion 9 from the spike neck downwardly is of uniform diameter throughout its length and has the largest diameter of any portion of the shank. This shank portion 9 constitutes the spike hole plugging section of the spike. The under end of this spike hole plugging section 9, tapers curvingly downwards into an intermediate shank section 10 of lesser diameter than section 9. The under end of the intermediate section 10 slopes annularly outwards into a shouldered under end section 11 of the spike on the under end portion of which section the walls 5 and 6 and wood cutting corners 8 are formed. The outward annular slope of the intermediate section 10 into the section 11 forms an annular shoulder 12 facing the head; and below this shoulder the diameter of section 11 is greater than the diameter of the intermediate section 10 and less than the diameter of the upper hole plugging section 9. Between the under end of the upper hole plugging section 9 and shoulder 12, the intermediate reduced section 11 is formed with a lengthwise extending, radially projecting rib 11^a. This rib also prevents axial turning of the driven spike and by reason of its location above the wood penetrating end permits the wood penetrating end to be varied, if desired, in cross-sectional form.

When such a spike is driven into resilient wood, the wood fibers in the wall of the spike hole formed, after having been initially pressed outwards, spring back into tight contact with the entire wall of the shank and the walls of rib 11^a so that the wood in the wall of the hole abuts downwardly as at 13 on the annular shoulder 12 and prevents the spike from backing out of its hole, axial turning of the driven spike in its hole being prevented as already described.

Our new spike, when driven into a wood

crosstie 14, for clamping a rail and rail plate P, either or both, in place on the crosstie, has the inward bearing surface 4 of the spike neck in proper bearing relation to the opposed vertical edge 15 of a rail base flange 16, the spike head extension 2 being driven downwardly into desired relation to the upper surface of the rail base flange.

The upper end section 9 of the shank being slightly larger than the maximum diameter of the under end section 11 of the spike so solidly compacts the fibers in the wall of the hole that a water and moisture excluding joint is formed. This is especially true in ordinary creosoted wood crossties.

What we claim is:

As a new article of manufacture, a railroad spike having a laterally flanged head formed with a rail base flange clamping ²⁰ tension; a neck formed with an inward rail base flange edge bearing wall; and a cross-sectionally round, straight shank having

variant diametric sections, the upper section adjacent the neck being of the greatest diameter and forming a spike hole plugging section; the downwardly adjacent intermediate section being of the smallest diameter and merging at its lower end into an under section having a diameter greater than that of the intermediate section and less than that of the upper hole plugging section, the upper end of said under section being formed with an upwardly facing, wood engaging shoulder, its lower end being downwardly tapered into a wood penetrating end, and ²⁵ ³⁰ said intermediate portion being provided with a lengthwise extending rib for prevention of axial turning of the driven spike.

Signed at New York in the county of New York and State of New York this 29th day ⁴⁰ of April, A. D. 1925.
